DISPENSING CONTAINER FOR MILK OR THE LIKE

David D. Tompkins, Worthington, Ohio, assignor to The Corrugated Container Company, Columbus, Ohio, a corporation of Ohio

Continuation-in-part of design application Ser. No. 5,791, Feb. 13, 1967. This application May 22, 1967, Ser. No. 7,220

Term of patent 14 years

(Cl. D9—175)

The rear end-panel is formed with a single, transversely extending recess which is a continuation of the single band in the side panels.

The essential features of the design reside in the solid line portions of the drawings.

This design is a continuation-in-part of the design disclosed in my copending application, Ser. No. 5,791, filed Feb. 13, 1967, now Patent No. D. 209,894, granted Jan. 9, 1968.

I claim:

The ornamental design for a dispensing container for milk or the like, substantially as shown and described.
